Des. 185,499
Patented June 16, 1959

185,499

CANDY EGG DISPENSER

Victor S. Klein, Dallas, Tex., assignor to
T. R. Ewart, Irving, Tex.

Application December 8, 1958, Serial No. 53,698

Term of patent 14 years

(Cl. D34—2)

Fig. 1

Fig. 2

Fig. 3

Fig. 4

Fig. 1 is a front, elevational view of a candy egg dispenser showing my new design,

Fig. 2 is a rear, elevational view,

Fig. 3 is a side, elevational view, and

Fig. 4 is a top plan view.

The dominant features of my design reside in the portions shown in full lines.

I claim:

The ornamental design for a candy egg dispenser, as shown and described.
